ELECTRICALLY DRIVEN STRIKING TOOL

Richard Dederer, Stuttgart, Germany, assignor to
 Kapital & Industriewerte A. G., Basel, Switzerland

Application December 22, 1933, Serial No. 703,651
 In Germany November 23, 1932

4 Claims. (Cl. 125—33)

Electrically driven striking tools controlled by means of plane cams comprise one or more striking bodies, which act upon a resilient ram.

According to the present invention the cross section of each striking body is in the shape of a sector of a circle, so that all the striking bodies unite together to form a cylinder coaxial with the ram.

One form of construction of the invention is illustrated by way of example in the accompanying drawing, in which

Figure 1 shows the striking tool in longitudinal section through the hammer casing, together with the driving means.

Figure 2 is a cross section showing the arrangement of the hammers, and

Figure 3 is a diagrammatic view of the individual hammer as it leaves the plane cam.

In a casing *a* are slidably mounted four hammers *b*, *c*, *d* and *e*, in such a way that their segmental cross sections together form a circle, as indicated in Fig. 2. Each hammer therefore has three guiding surfaces, two of which serve at the same time for guiding the two adjacent hammers. The hammers are longitudinally slidably independent of one another, and are pressed slowly by a plane cam *g*, in the sequence indicated, against a spring *o*, and, after reaching their highest point, are liberated so that they spring back on to the ram *f* of the tool without any obstruction. This unhampered blow is obtained by the quick yielding of a pendulum member *h* (Fig. 3), rockably arranged on the hammer, with a guiding roller *t*. In this figure the operation is diagrammatically illustrated, the cam *n* moving in the direction of the arrow. The tool ram *f* rests upon an antagonistic spring *m*, which has to take up the blows when the tool is working idly, an abutment pin *s* limiting the recoil of the ram. The wheel *g* of the plane cam is driven by means of toothed-wheel counter-shaft gearing *p*, *i*, *k* from an electric motor *l*. The motor itself is switched on and off by means of a switch lodged in a known manner in the interior of a handle *u*. Since the ram *f* forms the radial guide for the controlling cam *g*, a rotation of the tool ram *f* takes place simultaneously with each blow. This rotation may be effected positively by providing the ram with a tappet in the form of a wedge *w* or similar auxiliary means slidably

guided in a slot *v* of the control cam, or conversely. Balls *r* serve for taking up the spring pressure.

Having now particularly described and ascertained the nature of my said invention and in what manner the same is to be performed, I declare that what I claim is:—

1. In an electrically driven striking tool, individual striking bodies, a cam disc for controlling the striking bodies, and a ram carrying the tool itself, the striking bodies being so arranged as to fall upon the ram as the cam disc rotates, each striking body having a cross-section in the form of a sector of a circle and all the striking bodies together forming a cylinder coaxial with the ram.

2. In an electrically driven striking tool, individual striking bodies, a cam disc for controlling the striking bodies, and a ram carrying the tool itself, the striking bodies being so arranged as to fall upon the ram as the cam disc rotates, each striking body having a cross-section in the form of a sector of a circle and all the striking bodies together forming a cylinder coaxial with the ram, the cam disc being formed with a bore, and the ram fitting into this bore in such a way that when the cam disc rotates the ram is rotated with it.

3. In an electrically driven striking tool, individual striking bodies, a cam disc for controlling the striking bodies, a ram carrying the tool itself, the striking bodies being so arranged as to fall upon the ram as the cam disc rotates, each striking body having a cross-section in the form of a sector of a circle and all the striking bodies together forming a cylinder coaxial with the ram, and a radial coupling between the cam disc and the ram.

4. In an electrically driven striking tool, individual striking bodies, a cam disc for controlling the striking bodies, a ram carrying the tool itself, the striking bodies being so arranged as to fall upon the ram as the cam disc rotates, each striking body having a cross-section in the form of a sector of a circle and all the striking bodies together forming a cylinder coaxial with the ram, a pendulum member on each striking body and a roller on each pendulum member, the said roller bearing upon the cam disc.
